UNITED STATES PATENT OFFICE.

GEORGE H. TREADGOLD, OF PORT HURON, MICHIGAN.

CUFF-LINK.

1,256,745.

Specification of Letters Patent. Patented Feb. 19, 1918.

Application filed May 11, 1917. Serial No. 167,858.

To all whom it may concern:

Be it known that I, GEORGE H. TREADGOLD, a citizen of the United States of America, residing at Port Huron, in the county of St. Clair and State of Michigan, have invented certain new and useful Improvements in Cuff-Links, of which the following is a specification, reference being had therein to the accompanying drawings.

10 This invention relates to cuff links or buttons, and has special reference to a link or button which will readily adjust itself as a cuff is pulled up on the arm to allow the confronting edges of the cuff to separate 15 and permit of the cuff being raised sufficiently to prevent soiling. The advantages of such a cuff link or button are apparent to dentists, doctors, automobilists and others who have to wash their hands often, or perhaps work that would cause the cuffs to become soiled in normal position. At present, a proper fitting cuff cannot be pulled very far upon the arm, and will not remain in a raised position during much use of the hand.

20 To permit of the confronting edges of the cuff separating, when the cuff is elevated on an arm, is the principal object of my invention, and this is attained by a cuff link or button having one end thereof yieldably 25 held relative to the other, the means for yieldably holding the ends or heads of the link or button also constituting means for frictionally holding the cuff in a raised position on the arm.

30 Another object of my invention is to provide a cuff link or button having separable heads or ends and connecting means that holds the heads of the link or button normally in proximity to each other, thus maintaining the longitudinal edges of the cuff in contact and proper relation so as to present the usual and neat appearance.

A further object of my invention is to accomplish the above and other results by a 35 simple, durable and inexpensive construction which will be hereinafter specifically described and then claimed, and reference will now be had to the drawing, wherein

Figure 1 is a perspective view of a cuff 40 having the edges thereof held by a link in accordance with my invention;

Fig. 2 is a similar view of the same show-

ing the edges of the cuff separated and yet connected by the cuff link;

Fig. 3 is a perspective view of the cuff 55 link;

Fig. 4 is a plan of a take up member of the cuff link, showing the same in an unlocked position;

Fig. 5 is a similar view showing the take 60 up member in locked position;

Fig. 6 is a cross sectional view of the take up member, and

Fig. 7 is a plan of a modified form of member.

In the drawing, 1 denotes the link or button head having a central stud 2 and suitably connected to said stud, is a take up member, comprising a cylindrical casing 3 having a detachable cover 4. In the cylindrical casing 3 is a central stud or post 5 and suitably connected thereto is the inner convolution of a spiral band spring 6 which has the outer convolution thereof provided with an offset portion 7 adapted to engage 75 in the notch 8 provided therefor in the wall of the casing 3, said notch and the offset portion co-operating to hold the spring 5 expanded or in normal position, as shown in Fig. 5.

Suitably attached to one of the outer convolutions of the spring 6 or a member to move therewith, is a small chain or flexible connection 9 extending through an opening 10 in the cylindrical wall of the casing 3, 85 said opening being in proximity to the notch 8 of said casing. The chain 9 is provided with a head or member 11 to limit the inward movement of said chain into the casing 3 by the spring 6 and said chain extends 90 through an eye or staple 12 of a link or button head 13 and is attached to the casing 3, as at 14.

The heads 1 and 13 are susceptible to any desired ornamentation, and with the 95 spring 6 expanded in the take up member casing 3, the head 13 is held in proximity to the head 1, and when in a cuff, as shown in Fig. 1, the edges of the cuff are held in the usual manner, but when the cuff is 100 pulled upwardly on the arm, the spring 6 is placed under tension by the chain 9 passing out of the casing 3, and the edges of the cuff may separate, as shown in Fig. 2.

As the spring 6 is placed under tension, the offset end 7 thereof rides against the inner wall of the casing 3 and immediately upon the cuff being restored to normal position, the expansive force of the spring 6 is sufficient to pull the chain 9 into the take up member until the offset end of the spring engages in the notch of the casing, thereby temporarily holding the spring in 10 a locked position or until such time that the edges of the cuff are forcibly separated by pulling the same upwardly on the arm.

In Fig. 7 of the drawing, there is illustrated, a modified form of locking device, 15 wherein a small star wheel 15 is rotatable in an opening 16 of the take up member, and this star wheel is adapted to engage the outer convolution of the spiral spring and hold the same against accidental contraction. By simply shifting the star wheel with the finger the outer convolution of the spring may be released to permit of the 20 chain being withdrawn from the take up member.

25 The heads 1 and 13 of the cuff link are adapted to be placed in the usual cuff button holes provided therefor, but when the heads are of such size as to preclude their passage through the button holes, the stud 30 2 and the eye 12 may be made detachable relative to said heads.

It is thought that the operation and utility of the cuff link will be apparent without further description and while in the drawing 35 there is illustrated the preferred embodiment of my invention, it is to be understood that the structural elements are sus-

ceptible to such variations and modifications as fall within the scope of the appended claims.

40 What I claim is.

1. A cuff link comprising heads, a casing carried by one of said heads, and a chain movable in and out of said casing and adapted for holding the other of said heads. 45

2. A cuff link comprising heads, a casing carried by one of said heads, a chain attached to said casing and loosely connected to the other of said heads and extending into said casing, and means within said casing 50 adapted to retract said chain therein.

3. A cuff link of the type described, comprising heads, a casing carried by one of said heads, a flexible connection attached to said casing and loosely supporting the 55 other of said heads and extending into said casing, and a spiral spring in said casing adapted to draw said flexible connection therein.

4. A cuff link of the type described, comprising heads, a casing carried by one of said heads, a chain attached to said casing loosely connected to the other of said heads and extending into said casing, a coiled 60 band spring in said casing adapted to draw the chain therein, and means adapted for holding the chain in a retracted position in said casing. 65

In testimony whereof I affix my signature in the presence of two witnesses.

GEORGE H. TREADGOLD.
